UNITED STATES PATENT OFFICE

2,561,845

CLASP FOR PAINT BUCKETS, ETC.

Avery R. Curry, Louisville, Ky.

Application October 4, 1946, Serial No. 701,177

5 Claims. (Cl. 248—148)

1

This invention relates to a holder or clasp for paint buckets, tool boxes and other objects to engage and grip the seams of a tin roof of a house or building to support such objects when painting or working on such a roof and to keep the same from sliding down the roof when on an incline.

An object of the invention is to provide a holder or clasp of the character stated which may be readily moved from one part of a roof to another so as to be easily disengaged from one seam and engaged with another seam on another part of the roof so as to tightly grip or clasp the same in order to hold the bucket, box or other object in position against sliding or downward movement on the roof automatically under the weight of the bucket and paint contents or the like, box or other object by the mere positioning of the object over another seam.

Another object of the invention is to provide a holder or clasp of the class described having gripping jaws for tightly holding the object on the seam of the roof, and arms which engage the roof on either side thereof to force the jaws into clamping engagement with the seam, and means to prevent the arms or legs from dropping down when the bucket, box or other object is raised to be moved to another position, so as not to interfere with the automatic and convenient engagement of the jaws with another seam in a different position.

Another object of the invention is to provide means for tightening the holder or clamp on a bucket or like object so as to retain the bucket in position to be supported and clamped to the seam of a roof.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the holder or clasp for supporting a bucket on an inclined tin roof.

Figure 2 is a top plan view of the device detached from the bucket.

Figure 3 is a rear elevation showing the connection at the back of the bucket.

Figure 4 is an enlarged sectional plan view of the clasp or clamping device for engaging a roof seam.

Figure 5 is a front elevation of the device shown in Figure 4.

2

Figure 6 is a plan or face view of the clasp or clamp bracket.

Figure 7 is a side elevation of the structure shown in Figure 6.

Figure 8 is a view similar to Figure 6 of the modification.

Figure 9 is a side elevation of the structure shown in Figure 8, and

Figure 10 is a detailed view showing a fragment of the structure shown in Figure 5 in a release position.

Referring to the drawings in detail, in which like reference characters designate corresponding parts throughout the several views, 10 designates a building having a sloping tin roof 11 composed of strips joined to provide seams 12 of the usual type and with which the present device cooperates to support buckets, tool boxes or other objects on an inclined tin roof to keep the same from sliding or falling off of the roof. While the device may be used to support buckets, tool boxes or other objects, it is shown in connection with a paint bucket 13 having the usual bail and consists of a blank sheet of metal or a blank 14 having lateral side extensions or tongues 15 tapering in opposite directions and having offset angularly extending lugs 16 at the ends thereof provided with holes 17. The blank is also provided with a vertical tapered extension or tongue 18 to engage the front of the bucket or box thereabove and serve as a holder or retainer. In addition, the blank has a downward extension 19, which may be bent forwardly as indicated at 20 and then rebent rearwardly as at 21 in contact with the portion 20 which extends forwardly at right angles to the blank proper, thus providing a rearwardly extending horizontal shoulder or seat upon which the front edge portion or bottom of the bucket or box may rest. The extension 19 is then bent downwardly and inwardly as at 22 and is provided with a rounded or circular end having a hole therethrough. A vertically slotted extension 23 of channel shaped cross-section is slidably fitted on the end 22 and adjustably bolted at

20 24 through the hole in end 22 and the vertical slot in extension 23 to permit vertical adjustment or extension to enable leveling of the bucket 13 on roofs of different slopes. This structure is shown in Figures 6 and 7, whereas the modification shown in Figures 8 and 9 has the lower extension 19' bent forwardly as at 20' and then downwardly as at 22' instead of being bent inwardly or rearwardly as at 21 and 22, and may be provided with a hole near the lower end.

55 Otherwise, the structure is the same as described

in connection with Figures 6 and 7 and is disposed against the front of the bucket or box, as shown in Figure 1 of the drawings.

In order to fasten the device to a box, it may be simply fastened by nails or screws through the holes 17 but in order to fasten the same to a bucket, a holder, clamping structure or clasp is employed, as shown in the drawings and particularly Figures 1 to 3 inclusive, and 4, 5 and 10. For this purpose, the extension 23 is provided with a hole 25 near the bottom which receives a pivot 26 consisting of a countersunk rivet or bolt 26 on which a pair of oppositely outwardly extending arms or legs 27 are pivotally engaged by means of eyes 28 and 29 on the inner ends of legs 27. These eyes may be provided with a camming or bevelled contact toward each other or a straight contact as indicated at 30 and are mounted on the pivot 26 which is then passed through the hole 25 so that the head 31 is against one of the eyes or rings such as 29 and the other is against the extension 23 to be retained by the rivet head 31 in proper frictional engagement to permit the same to move of their own weight. The arms extend outwardly and may be arched upwardly and are provided with downturned ends 33 forming feet or legs designed to engage at their sharp or pointed lower ends with the roof 11 at either side of a seam 12 so as to press upwardly thereon at the outer ends of the legs or arms and force the depending jaws 34 at the inner ends thereof inwardly toward each to tightly grip or clasp the seam 12 on opposite sides thereof. These arms or jaws 34 are provided with oppositely extending stops or lugs 35 below the enlargements at the inner ends of the arms 27, so as to engage the latter when moving upwardly to limit the downward swing of the arms 27. The purpose of this is to prevent the arms 27 from dropping downwardly in such a manner as to interfere with the convenient placing of the bucket, the box or other object in a different position on the roof and the automatic engagement and clamping of the jaws 34 against the opposite sides of the seam 12 when the bucket or other object is moved about from one position to another as the work progresses. Obviously, since the lugs which limit the downward movement of the legs or arms 27 are positioned upon opposite sides of the pivot 26 formed by the bolt, they will prevent the arms or legs from swinging down too far to interfere with the placing of the bucket in a new position, but will move down sufficiently to permit the jaws 34 to be open or spread apart sufficiently to easily engage over a seam 12 and wider than the thickness of the seam, so that when placed in position and the legs 33 engage a roof on either side of a seam, the jaws will be forced together and the stop lugs 35 will move downwardly out of engagement with the horizontal portions of the legs at 27, to permit tight gripping or clamping of the seam and prevent the bucket or other object held by the device from sliding or moving down the inclined tin roof so as to be in convenient position for use by the worker supported on a scaling ladder or other support on the roof.

In order to retain the device in position around the bucket, the holes 17 may be engaged by the ends of cord, wire or other flexible sections 36, which may be knotted or twisted in any suitable manner as indicated at 37, in order to anchor the same. They are then extended around the bucket and may be passed through the holes 17 of the members shown in Figures 8 and 9 of the

drawings with the extensions 22' resting on the roof to support the bucket or with the members shown in Figures 6 and 7, although the latter is primarily adapted for use at the front of the bucket. The brackets shown in Figures 8 and 9 may be reversed in position so that the bucket is supported on the ledges or horizontal seat portions 20'. The ends of the cord or wire sections 36 are then tied or anchored through connecting lugs 38 as shown in Figures 1, 2 and 3 of the drawings, the same being sheet metal or cast metal triangular plates with side wings 39 apertured for anchoring the ends of the cord sections or wires 36 thereto by tying, bending or otherwise, as indicated at 40 through the holes 41. The inner ends have right angularly turned end-portions 42 provided with holes to receive a connecting bolt 43, so that the ends may be drawn together at the back of the bucket to tightly clamp the device around the same near the bottom of the bucket and thus firmly retain the bucket in position in the holder. Also, it is to be understood that the connections 36 may be provided with supports or legs in any other desired way, at the sides and toward the back of the bucket, and that any other suitable means may be provided for connecting and drawing the rear ends of the cords or wire sections 36 together to tightly clamp the device to a bucket at the back. If the camming surfaces 30 of the eyes 28 and 29 are employed to pivotally mount the legs 27, they will tend to hold or force the legs together so that the lugs will more effectively engage under the legs, since the inner end of each leg is provided with the lateral projection forming the stop lugs 35 as described, but the bolt must be sufficiently loose to permit the legs to swing downwardly under their weight without being too loose. The stops or lugs will also prevent the legs from dropping and extending down straight when the bucket is picked up to interfere with the positioning of the bucket in a new part of the roof and proper engagement of the jaws with a seam. Obviously, the legs 27 may be made of wire, sheet metal or otherwise, within the purview of the invention and that it is not desired to be limited to any particular material, and that the legs may be rectilinear, or arched upwardly and the leg portions 33 which engage the roof on either side of a seam may extend straight down or slightly inwardly, in order to better grip the seam at the jaws 34, which may have their lower ends extending downwardly or slightly outwardly to facilitate entrance of the seam between the jaws. The device can be very cheaply and economically produced to admirably serve its purposes for supporting buckets, containers, tool boxes or other objects on a roof for convenient access by the worker, painter, or other person working on the roof and moved to any position desired at the seams thereof.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. A holder for use on a seamed roof comprising a member designed to engage the front of the object which is held and adapted to seat thereon, and outwardly extending legs pivoted to said member and having depending ends to engage the roof and provided with jaws at their inner

ends for engaging a roof seam, said jaws being automatically clamped to the seam upon engagement of the legs with the roof.

2. A holder for use on a seamed roof comprising a member designed to engage the front of the object which is held and seated thereon, outwardly extending legs pivoted to said member and having depending ends to engage a roof and provided with jaws at their inner ends for engaging a roof seam, said jaws being automatically clamped to the seam upon engagement of the legs with the roof, and means to limit the downward swing of the legs and separation of the jaws.

3. A holder for use on a seamed roof comprising a member designed to engage the front of the object which is seated thereon, legs pivoted to said member to engage the roof and provided with jaws for engaging a roof seam and automatically clamping on the seam upon engagement of the legs with the roof, said member having opposite side extensions and a vertical extension, flexible members attached to said side extensions, seat supporting members mounted on said flexible members to engage the sides of the object, adjustable connections between the ends of the flexible members at the back of the object, and means to limit the separation of the jaws and downward swing of the legs to an open position of the jaws for engagement with a roof seam.

4. A holder for use on a seamed roof comprising a bracket member formed of a blank having side extensions with apertured ears, a vertical extension and a depending portion rebent to provide an offset seat portion, legs extending outwardly and pivoted to said downward extension below the seat on which a bucket is adapted to be supported, lugs on the ends of the legs adapted to engage beneath the leg portions at the opposite sides of the pivot of the legs to limit the downward swing of the legs, said legs having depending spaced jaws at their inner ends and depending outer ends to engage the roof at either side of a seam, said jaws adapted to clamp the seam

when the legs engage the roof at either side thereof at the depending portions, and means for fastening the bracket to an object to be supported such as a bucket.

5. A holder for use on a seamed roof comprising a bracket member formed of a blank having side extensions with apertured ears, a vertical extension and a depending portion rebent to provide an offset seat portion, legs extending outwardly and pivoted to said downward extension below the seat on which a bucket is adapted to be supported, lugs on the ends of the legs adapted to engage beneath the leg portions at the opposite sides of the pivot of the legs to limit the downward swing of the legs, said legs having depending spaced jaws at their inner ends and depending outer ends to engage the roof at either side of a seam, said jaws adapted to clamp the seam when the legs engage the roof at either side thereof at the depending portions, flexible members connected to the ears of the extensions, similar brackets having offset portions supporting the bucket at the sides thereof and receiving said flexible connections through the ears thereof, brackets at the ends of the flexible connections, and means connecting said brackets to draw the same together to tightly clamp around a bucket near the bottom thereof, whereby the bucket is prevented from moving or sliding downwardly on the roof at the seam.
